US00D499075S

(12) **United States Design Patent** (10) Patent No.: **US D499,075 S**
Yoon et al. (45) Date of Patent: **** Nov. 30, 2004**

(54) **LIGHT-EMITTING DIODE**

(75) Inventors: **Joon Ho Yoon**, Seoul (KR); **Jung Kyu Park**, Kyungki-do (KR); **Young Sam Park**, Seoul (KR)

(73) Assignee: **Samsung Electro-Mechanics Co., Ltd.** (KR)

(**) Term: **14 Years**

(21) Appl. No.: **29/199,049**

(22) Filed: **Feb. 9, 2004**

(30) **Foreign Application Priority Data**

Jan. 14, 2004 (KR) 30-2004-0000997

(51) LOC (7) Cl. **13-03**

(52) U.S. Cl. **D13/180**

(57) **CLAIM**

The ornamental design for a light-emitting diode, as shown and described.

DESCRIPTION

FIG. 1 is a perspective view of a light-emitting diode of the invention;

FIG. 2 is a front view thereof;

FIG. 3 is a left side view thereof;

FIG. 4 is a top plan view thereof; and,

FIG. 5 is a bottom view thereof.
